UNITED STATES PATENT OFFICE.

JOHN E. ARTHUR, OF LANE, ILLINOIS.

ROTARY ENGINE.

SPECIFICATION forming part of Letters Patent No. 699,740, dated May 13, 1902.

Application filed November 16, 1900. Serial No. 36,669. (No model.)

To all whom it may concern:

Be it known that I, JOHN E. ARTHUR, of Lane, in the county of DeWitt and State of Illinois, have invented certain new and useful Improvements in Rotary Engines, of which the following is a specification.

This invention is exemplified in the structure hereinafter described, and it is defined in the appended claims.

10 In the drawings forming part of this specification, Figure 1 is a side elevation of an engine constructed in accordance with my invention. Fig. 2 is a plan of the engine. Fig. 3 is a representation of the interior of one-half of the cylinder casing, showing the frame or bed and the heads of the cylinders in cross-section. Fig. 4 is a representation of the exterior surface of one of the cylinder-casings, showing a cone with steam-passages 15 and cut-offs or bridges therein. Fig. 5 is a detail of the conical bearing in which the steam-passages and cut-offs are located, the valve-casing or steam-chest and one of the boxes being shown in section. Fig. 6 is a 20 perspective representation of the quarter-boxes and slides for the crank-shaft. Fig. 7 is a perspective representation of one of the wedges used to take up wear in the quarter-boxes and the slides. Fig. 8 is a detail 25 of a valve used to draw water from the cylinder-casing.

The frame or bed-plate 1 of the engine is of any suitable construction, and it provides horizontal bearings for the crank-shaft 2. 30 The crank-shaft is held against rotation while the engine is working. One of its ends is journaled or has bearings in the cylinder-casing and its other end extends through a bearing of the cylinder-casing. An arm or 35 lever 3 is fastened onto the protruding end of the crank-shaft, and it has a set-screw 4, which is set into one of two holes, as 5, in the frame to hold the crank-shaft in one or the other of its operative positions. The cylinder-casing is preferably cylindrical in general 40 outline and concentric with the body of the crank-shaft. It is composed of two parts 6 and 9, which are secured together by screws 7, passing through part 6 and entering screw-holes 25 in part 9 or in any suitable manner. Cylinders 20 are formed in the casing diamet-

rical therewith. Cylinder-heads 11 are secured in the perimeter of the casing by screws 12 and conform to the curvature thereof. A pair of pistons 22 are fastened rigidly to opposite sides of a cross-head 23, and the cross-head is slotted at right angles with the axes of the pistons to receive the crank 2^a of the crank-shaft 2, as shown in Fig. 3. The crank is journaled in quarter-boxes 26^a, and special provision is made for taking up the wear of the quarter-boxes and the slides therefor, as will hereinafter appear. The cross-head has slide-bearings 24 in the cylinder-casing, which aids in keeping the movements of the pistons 55 diametrical with relation to the casing and the crank-shaft therein. The protruding end of the crank-shaft journals in boxing 18. It extends through a stuffing-box 19 and into the casing. Its crank is in line with the 60 centers of the pistons, and its inner end has a bearing in spindle 26 of the part 9 of the casing or in the wall of such part of the casing. The spindle 26 is made conical at 27, and in the conical surface is formed a pair of 65 grooves 28, that act as passages for live steam and exhaust alternately. These grooves are circumferential of the conical surface, and they are separated by bridges or solid portions 29, which constitute cut-offs for the 70 steam. A collar 13 is interiorly conical to conform to cone 27, and it is bored to form a 75 steam-chest. Its end 14 provides a connection for a steam-pipe and its end 15 provides a connection for an exhaust-pipe. The bores 80 of the collar communicate each with opposite grooves of the cone alternately, the movements of the bridges past the bores acting to shift the communications. The cone terminates beyond the steam-chest collar in a shaft 85 31, on which the drive-wheel 17 is mounted, and a box 16 supports shaft 31 between the drive-wheel and the cone. The box 16 is grooved circularly in its face adjoining the collar, as shown at 32 in Fig. 5, and a spiral 90 spring 33 rests in the groove of the box and exerts pressure on the collar, tending to force it in contact with the cone. A lateral rib or reinforcement 10 extends diametrically across the outer face of part 9 of the cylinder-casing, and in such rib are steam-passages 30, 95 that connect the grooves in the cone with 100

openings or ports 21 in the outer ends of the cylinders of the engine. The steam-passages 30 extend through spindle 26 to the rib 10, and thence extend radially with relation to 5 the cylinder-casing.

To provide means for draining the engine of any water it may contain to prevent damage from freezing, for instance, a groove 37 is formed in the inner edge of one of the 10 parts of the cylinder-casing and is made to communicate at its ends with the interior of the cylinder outside the pistons. A plug-valve 36 is set crosswise of the groove at the center thereof and is provided with a passage-way or slot 36^a, that establishes communication between the two parts of the groove when the plug is turned in the proper direction. The plug is bored longitudinally inward from the slot 36^a, and a cross-bore 20 (shown in dotted lines in Fig. 8 at 36^b) penetrates the plug at right angles with the slot thereof. A pipe 38 establishes a communication between the cylinder-casing inside the pistons and the plug 36, and when the plug 25 is turned with its slot in line with the groove 37 the bore 36^b lines up with pipe 38 on one side and the outlet 39 (shown in dotted lines in Fig. 5) on the other side and provides an outlet for all the water on both sides of the 30 pistons.

The boxing for the crank of the crank-shaft comprises the quarter-boxes 26^a, set inside the slide-boxes 34 crosswise thereof and with room at the ends of the slide-boxes for wedges 35. The wedges are pyramidal or tapered both ways, and their tendency is when tightened to force the quarter-boxes against the crank-bearing and the slide-boxes against the cross-head bearings. The slide-boxes are 40 flanged on one side to embrace or overlap the cross-head bearings and the quarter-boxes are flanged on the opposite side for the same purpose. The wedges 35 are bored lengthwise and screw-threaded, and screws 27^a (seen 45 only in Fig. 3) extend through the quarter-boxes and into the smaller ends of the wedges. A plug 8 in Fig. 1 is set into the cylinder-casing in circular alinement with the screws 27^a of the boxes, and when it is desired to take 50 up wear in the boxes of the crank the plug 8 is removed, the casing and the crank are moved until one of screws 27^a is in line with the plug-opening, when a screw-driver is inserted through the opening and the screw is 55 made to draw the wedge small end foremost into the space between the parts of the crank-boxes and to spread such parts in directions to take up all wear. Next the other screw 27^a is brought into alinement with the plug-opening and tightened, and finally the plug 60 is replaced.

In operation the cylinder-casing revolves while the pistons reciprocate in their cylinders. The crank of the crank-shaft forms a 65 bearing against which the pistons push while taking steam and moving from their nearest

approach to the center of the engine to their greatest distance therefrom. Each cylinder takes steam throughout one half of a complete rotation of the engine, approximately, 70 and exhausts during the other half-rotation. Steam is admitted as a port-groove 28 of the cone moves into communication with the steam-port of the steam-chest collar 13, and it is exhausted after such groove is out of 75 communication with the live-steam supply and in communication with the exhaust. The bridges 29 separate one groove 28 from the other groove in the cone, and the lengths of the bridges determine for how long in its 80 semirotation each cylinder may receive live steam. As shown in the drawings, the bridges are quite short, and so the live steam is supplied for nearly the entire semirotation of each cylinder or nearly all the time to the two 85 cylinders; but by making the bridges longer the steam will be supplied for a proportionately shorter time and expansion of steam will be utilized.

When it is desired to reverse the engine, 90 the lever 3 is turned to a position diametrically opposite that shown in Figs. 1 and 2, thus reversing the position of the crank of the crank-shaft, and the push of the pistons against the crank will then be exerted in a direction opposite that developed in the shown correlation of parts. The collar 13 is held against rotation with the cone, but it is free to move lengthwise of the axis of the cone, and the spring 33 automatically takes up wear 95 in the cone and the collar by forcing the collar against the cone.

The bearing for the drive-shaft is between the cone and the drive-pulley, and so steam does not pass through the bearing to heat it 100 injuriously.

The cross-head is fixed at right angles with the paths of the pistons, and as the pistons push against the crank the friction developed in the cross-head is utilized in giving the cylinders a tilt in the direction to produce rotary motion in the cylinder-casing.

The right to claim the boxing comprising the pair of slide-boxes containing a pair of quarter-boxes, pyramidal wedges between the quarter-boxes and the slide-boxes, and screws in the small ends of the wedges, in other environments and combinations than those herein shown, is hereby reserved.

I claim—

1. In a reciprocating rotary engine, a circular casing for the diametrical cylinders having a groove communicating with the outer ends of the cylinders, a pipe running from the space between pistons to the groove and a three-way valve at the intersection of the pipe with the groove, substantially as described.

2. In a rotary engine, the combination of a stationary crank-shaft, a pair of pistons connected together by means of a cross-head that connects slidably with the crank of the crank-

shaft, a pair of quarter-boxes embracing the crank, a pair of slide-boxes containing the quarter-boxes and fitting in the slot of the cross-head, pyramidal wedges between the 5 quarter-boxes and the slide-boxes and screws in the small ends of wedges, substantially as and for the purpose described.

In testimony whereof I sign my name in the presence of two subscribing witnesses.

JOHN E. ARTHUR.
